SYSTEM OF MODULATION UTILIZING A
CATHODE FOLLOWER

Jack M. Glessner, Dayton, Ohio

Application September 4, 1945, Serial No. 614,341

4 Claims. (Cl. 179—171.5)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates to a system of modulation employing a cathode follower and which is suitable for use in signal generators and in low and moderate power transmitters.

A principal object of this invention is to provide a modulator utilizing a cathode follower which allows modulation at practically any frequency.

Another object is to provide such a modulator which has very little audio distortion.

These and other objects will become apparent in the specification and in the appended drawing in which Figures 1 and 2 illustrate schematically the circuit and arrangement of elements in the modulator.

In the drawing 9 and 10 are the terminals receiving the modulating voltage. A condenser 11 is in series between terminal 9 and the grid of a cathode follower tube 12. Between terminal 10 and the cathode of tube 12 are resistors 14—15 connected at their junction to resistor 13 to provide correct bias voltage. The cathode is further connected through radio frequency choke coil 16 to a radio frequency by-pass condenser 19 grounded as shown. The output end of choke 16 is connected to the tuned circuit comprising inductor 17 and variable condenser 18 which are in turn connected to the plate of tube 20, the latter elements comprising a modulated R. F. amplifier. The modulated R. F. output is taken from terminals 22 and 23 of coupled pickup coil 21.

In operation, the cathode follower develops a D. C. voltage across resistors 14 and 15. This voltage is roughly half the B voltage applied to the cathode follower from the B voltage supply. This developed D. C. voltage is applied to the plate, screen, or other element or elements, of tube 20 to be modulated. In the example illustrated the voltage is applied to the plate of tube 20. When audio voltage is applied to the control grid of the cathode follower the developed D. C. voltage provided across 14—15 varies at the audio rate and effects modulation of the modulated R. F. amplifier. One of the advantages of the invention disclosed is that it permits modulation at practically all frequencies with almost no distortion.

Any disadvantage resulting from not reaching

2

100% modulation may be corrected by adding a resistance 200, Fig. 2, in series with choke 16 to lower the B voltage applied to the modulated R. F. amplifier, and by-passing the resistor to 5 audio by means of a condenser 202. Other means for lowering the D. C. potential supplied to the modulated amplifier 20, may be utilized to increase the maximum degree of modulation possible.

10 10 Extremely low audio frequencies, even going to D. C. input changes, may be used in the present invention by removing condenser 11 and by inserting a battery 204 for bias.

I claim:

15 1. A modulation circuit comprising a source of modulating signals, a first vacuum tube having an anode, a cathode, and at least one control electrode, said electrode being connected to said source, a cathode resistor grounding said cathode, a second vacuum tube having an anode, a cathode, and at least one control electrode, a source of carrier frequency connected to the control electrode of said second tube, and a coupling circuit between the plate of said second tube 20 and said cathode resistor, whereby said resistor furnishes varying anode potential for said second tube for varying the amplitude of said carrier frequency in said coupling circuit.

20 2. A modulation circuit as defined in claim 1 in which said coupling circuit includes a tank circuit and a carrier frequency choke connected between said tank circuit and said resistor.

25 3. A modulation circuit as defined in claim 1 in which said coupling circuit includes a tank circuit and serially connected carrier frequency choke and a resistance shunted with a by-pass condenser, for connecting said tank circuit to said cathode resistor.

30 4. A modulator circuit as defined in claim 1 in which the connection between the electrode of said first tube and said source of modulating signals is a connection responsive to direct current.

JACK M. GLESSNER.
